UNITED STATES PATENT OFFICE

2,680,409

CENTRIFUGAL PUMP

Carl R. Sebens, Bridgeport, Conn., assignor to
General Electric Company, a corporation of
New York

Application April 19, 1950, Serial No. 156,802

3 Claims. (Cl. 103—103)

1

This invention relates to a fluid pump of the impeller type.

Although the principal object of my invention is to increase the efficiency of impeller pumps, my invention is directed also to the provision of an impeller pump having unusual directional characteristics. For example, my invention when applied in one casing arrangement will provide a pump which will generate positive pumping head of large magnitude for one direction of rotation of the impeller and substantially no pumping head for reverse rotation of the impeller.

In accomplishing these objectives I equip a pump casing of relatively conventional shape with a novel inlet system comprising a curving channel which is concentric with the impeller and follows a predetermined arc on a radius not less than that of the root circle of the impeller blades. A wall or walls of the channel are arranged to effect a relatively uniform decrease in the cross-sectional area of the channel, the mouth thereof having the greatest area. I have found that the best results obtain when the terminus of the inlet channel is within the area of maximum radius of the casing scroll, and the mouth of the channel is displaced from the pump casing discharge in approximately the angular relation

360

 $\frac{N}{N}$

in which N is the number of impeller blades.

It is my present belief that the directional effectiveness and efficiency of a pump embodying my invention results from a better conversion of velocity head to static head than is obtained in conventional centrifugal pumps. In a conventional centrifugal pump, part of the total maximum head is created by centrifugal force and a lesser part of said total head is created by conversion of velocity head to static head. When the pump is operated in the forward direction, the velocity head adds to the centrifugal head to produce the total head, but when the pump is operated in reverse the velocity head subtracts from the centrifugal head and results in a decreased total head. The total maximum head produced in the unidirectional pump embodying my invention may be made up of nearly equal parts of centrifugal head and velocity head, so that when the pump is operated in the forward direction the velocity head is added to the centrifugal head, but when the pump is operated in reverse the velocity head subtracts from the centrifugal head to give practically no resultant head.

The foregoing discussion of performance will be better understood from a comparison of test results. A single-direction pump embodying my invention produced a positive pumping head of approximately ten feet of water pressure for one direction of impeller rotation and a negative

2

pumping head amounting to six inches of water pressure for opposite rotation. In contrast, a conventional center-entrance impeller pump of similar size and mechanical characteristics produced a positive pressure of about five and one-half feet of water for one direction of rotation and a positive head of about one and one-half feet of water for reverse rotation.

In the accompanying drawings Fig. 1 is a top plan view of a uni-directional pump embodying my invention, the arrangement and relationship of the impeller blades relative to the pump casing being indicated in dotted line; Fig. 2 is a side elevation of the pump of Fig. 1 with a portion of the casing wall broken away to show the commencement of the directional inlet; and Fig. 3 is a sectional elevation taken on the lines 3—3 of Fig. 1.

Referring initially to Figs. 1 and 3, an impeller pump embodying my invention comprises a main casing section 1 and a base plate 2 which collectively define a chamber 3 within which operates the impeller 4. Illustratively the said impeller comprises four rectangularly associated blades 5 rising from a circular web 6. The impeller is mounted on a shaft 7 suitably journaled in a casing neck 8 within an appropriate bearing 9 disposed therein. A seal of conventional pattern prevents escape of liquid along the pump shaft. It is to be understood that the impeller shaft is arranged to be rotated by any suitable driving means.

The inlet to the pump casing comprises a passage 11 having a mouth 12 the area of which is substantially that of the pump discharge 14. The roof 15 of the inlet passage slopes downwardly toward the top body wall 16 of the casing 1 and follows the counterclockwise direction of rotation of the impeller during its pumping operation. As appears from Fig. 1, the minimum radius of the passage 11 is greater than the root circle of the impeller blades 5. The collar 17, the wall of which provides an outer wall of the passage 11, provides means for affixing the pump to a conduit, tank or vat from which liquid is to be pumped. For example, it is contemplated that the pump will be used as a drainage pump for a clothes washing machine in which event the collar 17 will be clamped or otherwise secured to the neck of a drainage opening in the washing machine tub. Collar 17 also provides a structure within which a conventional strainer or vortex inhibiting baffle or screen (not shown) may be mounted.

The outlet connection 14 of the casing extends substantially tangentially therefrom. As is apparent from a comparison of Figs. 1 and 2, the area of the directional inlet 11, considering the bottom surface of the casing wall 16 as representing the bottom of the inlet passage, is greatest in the area of small casing radius and smallest at

the area of greatest casing radius, said last-named area comprehending the entry to the outflow connection 14. It will be noted also that the pump inlet 12 is somewhat more than ninety degrees removed from the inlet of the discharge connection 14. This departure from the previously noted relationship of

$$\frac{360}{N}$$

in which N is the number of blades in the impeller takes into consideration the thickness of the impeller blades in the area of the mouth of the inlet. The terminal line 13 of the passage 11 is preferably normal to the axis of the outlet 14.

The casing of the Fig. 1 embodiment is scroll shaped pursuant to conventional centrifugal pump practice. The discharge head from the pump therefore includes a substantial centrifugal force component. It is my belief that the improved performance of a pump having the inlet system embodying my invention derives not only from the shock reduction incident to causing the liquid to be introduced into the impeller casing flowing in the direction of rotation of the impeller but also to one or more of the further features of bringing the water into the pockets between the blades at a point radially beyond the impeller hub, distributing the inflowing water through an arc, and establishing a cross-sectional area of the inflow passage which decreases as the casing area beyond the blade tips increases. The above relationships appear to effect a dragging action exerted on the water in the inlet channel by the water being carried along by the impeller. The dragging action produces a head at the mouth of the inlet channel which may be less than the head occurring at the center of the impeller chamber if the impeller is rotated forward or which may be greater than the head occurring at the center of the impeller chamber if the impeller is driven in reverse.

The disposition of the inlet 12 ninety degrees or more from the pump exhaust (in a four-bladed impeller pump) prevents interference between the action occurring at the inlet and the action occurring at the outlet of the impeller chamber.

While I have shown a particular embodiment of my invention, it will be understood, of course, that I do not wish to be limited thereto since many modifications may be made; and I therefore contemplate by the appended claims to cover any such modifications as fall within the true spirit and scope of my invention.

What I claim as new and desire to secure by Letters Patent of the United States is:

1. An unidirectional flow pump including a multi-blade rotatable impeller, a casing for said impeller defining an involute pump chamber increasing in radius in positive direction of rotation around the axis of said impeller, an outlet from said casing extending from said chamber at its maximum radius, and directional inlet means into said chamber providing positive velocity head in the positive rotational direction, said means comprising an annular wall concentric with said impeller and extending outwardly from said casing, an arcuate passage enclosed by said annular wall and extending around the axis of said impeller displaced axially from and communicating with said chamber throughout, said passage decreasing in cross-sectional flow area in the positive direction of rotation from a mouth positioned with respect to said casing at an area of small chamber radius to a terminus at maximum cham-

ber radius, whereby rotation of said impeller in the positive direction results in a positive head while reverse rotation results in substantially no head.

- 5 2. A pump providing fluid flow only upon positive direction of rotation comprising a base plate, a multi-blade impeller mounted for rotation with respect to said base plate, means for rotating said impeller, a cover cooperating with said base plate to form a scroll casing enclosing said impeller and having a minimum internal radius with respect to the impeller rotational axis slightly exceeding the radius of said impeller and an increasing radius in the positive direction of rotation, means defining an outlet passage from within said casing at its maximum radius extending tangentially with respect to said casing, and means defining a directional inlet to said casing through said cover, said last mentioned means comprising an exterior annular wall portion extending outwardly from said cover concentric with the impeller axis, an arcuate and concentric inner wall of minimum radius greater than the radius of the root circle of said impeller blades, 25 and a roof portion interconnecting said exterior and inner walls inclined inwardly toward said casing in the positive direction of rotation, said roof and walls defining a passage commencing with a mouth of flow area substantially equal to the flow area of said outlet passage and located circumferentially in the positive direction of rotation from said outlet passage by at least the arc between adjacent impeller blades, said roof portion sloping inwardly toward said impeller 30 from said mouth to a terminus extending radially across said passage and having minimum clearance with respect to said impeller, the terminus of said passage being located substantially at said casing outlet passage, whereby fluid entering through said directional inlet is given an initial positive rotational velocity and is forced into the space between impeller blades by the gradual decreasing flow area of said passage progressing in the positive direction of rotation.
- 35 4. A pump providing fluid flow only upon positive direction of rotation including a multi-blade impeller, a casing for said impeller defining an involute pump chamber increasing in radius in the positive direction of rotation around the axis of said impeller, an outlet from said casing extending from said chamber at its maximum radius, and directional inlet means providing positive velocity head in the positive rotational direction, said directional inlet means comprising an exterior wall in the form of an annular collar 40 extending outwardly from said casing and concentric with the impeller axis, an inner arcuate wall concentric with said exterior wall and of a minimum radius exceeding the root circle radius of said impeller, and a roof interconnecting said exterior and inner walls inclined toward said chamber in the positive direction of rotation to define an inlet passage commencing with a mouth of cross-sectional area equivalent to said outlet and decreasing in cross-sectional area in the 45 positive direction of rotation.
- 50 5. A pump providing fluid flow only upon positive direction of rotation including a multi-blade impeller, a casing for said impeller defining an involute pump chamber increasing in radius in the positive direction of rotation around the axis of said impeller, an outlet from said casing extending from said chamber at its maximum radius, and directional inlet means providing positive velocity head in the positive rotational direction, said directional inlet means comprising an exterior wall in the form of an annular collar 55 extending outwardly from said casing and concentric with the impeller axis, an inner arcuate wall concentric with said exterior wall and of a minimum radius exceeding the root circle radius of said impeller, and a roof interconnecting said exterior and inner walls inclined toward said chamber in the positive direction of rotation to define an inlet passage commencing with a mouth of cross-sectional area equivalent to said outlet and decreasing in cross-sectional area in the 60 positive direction of rotation.
- 60 6. A pump providing fluid flow only upon positive direction of rotation including a multi-blade impeller, a casing for said impeller defining an involute pump chamber increasing in radius in the positive direction of rotation around the axis of said impeller, an outlet from said casing extending from said chamber at its maximum radius, and directional inlet means providing positive velocity head in the positive rotational direction, said directional inlet means comprising an exterior wall in the form of an annular collar 65 extending outwardly from said casing and concentric with the impeller axis, an inner arcuate wall concentric with said exterior wall and of a minimum radius exceeding the root circle radius of said impeller, and a roof interconnecting said exterior and inner walls inclined toward said chamber in the positive direction of rotation to define an inlet passage commencing with a mouth of cross-sectional area equivalent to said outlet and decreasing in cross-sectional area in the positive direction of rotation.
